COMBINED DISPOSABLE BRISTLE UNIT AND ADJUSTABLE PAINTBRUSH HANDLE

Bill G. Blount, 1417 Oak Lea Drive,
Irving, Tex. 75060

Filed Nov. 10, 1966, Ser. No. 4,618

Term of patent 14 years

(Cl. D9—2)

FIG. 1

FIG. 2

FIG. 3

FIG. 4

I claim:

The ornamental design for a combined disposable bristle unit and adjustable paintbrush handle, as shown.
